[57] CLAIM

The ornamental design for a combined shade and tungsten halogen lamp, as shown and described.

DESCRIPTION

FIG. 1 is a bottom perspective view of a combined shade and tungsten halogen lamp showing our new design, the broken lines being shown for illustrative purposes only;

FIG. 2 is a top plan view thereof;

FIG. 3 is a side elevational view thereof, all sides being identical; and,

FIG. 4 is a bottom plan view thereof.

The characteristic feature of our design resides in the contour of the curvilinear sides of the shade which terminate in a substantially flat band or lip on the outer rim, as best shown in FIGS. 3 and 4.
